UNITED STATES PATENT OFFICE.

ANDERSON WOODWARD AND JESSE E. COLE, OF LEEPER, MISSOURI.

WIRE-FENCE-STRETCHING CLAMP.

1,198,807.

Specification of Letters Patent. Patented Sept. 19, 1916.

Application filed December 4, 1915. Serial No. 65,125.

To all whom it may concern:

Be it known that we, ANDERSON WOODWARD and JESSE E. COLE, citizens of the United States, residing at Leeper, in the county of Wayne and State of Missouri, have invented certain new and useful Improvements in Wire - Fence - Stretching Clamps, of which the following is a specification, reference being had to the accompanying drawings.

Our invention relates to devices whereby wire fencing may be stretched, and particularly to the clamp for engaging the web of wire fencing.

15 The general object of our invention is to provide an improved clamp which when stretching force is applied to the fence will bind upon the wire web and securely hold it while the web is being pulled.

20 A further object of the invention is to provide a device of this character which may be readily applied, readily removed from engagement with the fence, which has two parts and these of a very simple construction.

25 Other objects will appear in the course of the following description.

Our invention is illustrated in the accompanying drawings, wherein:

30 Figure 1 is a face view of our clamping device applied to a fence shown in conjunction with a wire tightener of ordinary construction; Fig. 2 is an enlarged top plan view showing the crimping action of the 35 clamping bar 17; Fig. 3 is a top plan view, but showing the clamping bar 17 shifted to its released position.

Referring to these figures it will be seen that our clamp device comprises a base 10 40 which is preferably made of wood and has a length equal to or greater than the width of the web of wire fencing to be stretched or tightened. Passing through this base 10 are a plurality of bolts 11, the ends of which

45 are laterally curved as at 12 to form approximately semi-circular seats 13. The inner face of the base 10 confronting the seat 13 is recessed, this recess having an inclined face 14 and a wall 15 extending out 50 perpendicularly to the outer face of the base. Attached to the base 10 is a V-shaped or U-shaped bail 16.

Coacting with the base 10, which base forms one of the clamping elements, is a 55 clamping bar 17 which is preferably of steel or some like material and which is approxi-

mately rectangular in cross section, the edges, however, being rounded, as at 18. This clamping bar has a width somewhat less than the distance between the seats 13 of the hook-shaped members 11 and the face 14 of the recess in the base. Attached to the clamping bar 17 is a V-shaped or U-shaped bail 19, as noted from Fig. 1. The clamping bar 17 is mounted upon the extremities of this bail and is disposed at less than a right angle to the bail. Engageable with the bails 16 and 19 is a pull hook 20 which may be attached to any suitable wire stretching device or mechanism.

In the practical use of our invention the base 10 is disposed against one face of the web of fencing and the clamping bar 17 is engaged in the seats 13 in the manner illustrated in Fig. 3. The bail 19 is then to be 70 moved toward the bail 16, which will cause the rounded edge of the bar 17 to bear against and crimp the wire fencing into the recess 14 and securely lock it therein. Strain is then applied to the hook 20. The strain 75 on the web of wire will merely act to increase the binding action of the bar 17 and the greater the strain the tighter the bar 17 will engage with the fence. To release the clamp from the fence it is only necessary to relieve 80 the strain on the hook 20 and then shift the bail 19 away from the bail 16. It will be noted that the clamping bar 17 is of such a construction as to form an eccentric clamp which when the bail 19 is forced toward 85 16 will cause sufficient tension to hold the web A of wire securely while strain is being applied upon the pull hook and the fencing web. This clamp has been tried in practice and found to be extremely effective. When 90 the strain is applied to the bails the clamp binds securely upon the web and prevents the web from slipping through the clamp. It is readily attached, readily detached, and may be very cheaply made.

Having described our invention, what we claim is:

A tightening clamp of the character described including a base bar, hook-shaped bolts extending out from the base bar and 105 adjustable therethrough and formed with semi-circular seats, the inner face of the base bar opposite said seats being formed with an inclined recess, a clamping bar having one edge disposed in said seats, the opposite edge of the clamping bar being disposed within said recess, a bail attached to 110

the base bar, a bail attached to the clamping bar and extending at an angle thereto, said angle being less than a right angle, and a pull hook operatively engaging both of said 5 bails and holding the free end of the bail attached to the clamping bar in position against the other bail whereby to hold the clamping bar in clamping position.

In testimony whereof we hereunto affix our signatures in the presence of two wit- 10 nesses.

ANDERSON WOODWARD.
JESSE E. COLE.
